UNITED STATES PATENT OFFICE.

WILLIAM T. EMMES, OF CINCINNATI, OHIO.

SPEED-CHANGING DEVICE.

SPECIFICATION forming part of Letters Patent No. 712,279, dated October 28, 1902.

Application filed July 10, 1902. Serial No. 114,983. (No model.)

To all whom it may concern:

Be it known that I, WILLIAM T. EMMES, a citizen of the United States, residing at Cincinnati, Hamilton county, Ohio, have invented certain new and useful Improvements in Speed-Changing Devices, of which the following is a specification.

This invention, pertaining to improvements in speed-changing devices of geared type, will be readily understood from the following description, taken in connection with the accompanying drawings, in which—

Figure 1 is a diagrammatic side elevation of the isolated motion work of a speed-changing device exemplifying my invention; Fig. 2, a diagrammatic plan of the same; Fig. 3, an end elevation of a complete exemplifying mechanism embodying my invention; Fig. 4, a vertical transverse section of the mechanism in the plane of line *a* of Figs. 5 to 10, inclusive, the main supporting-frame to which the device is to be attached being omitted; Fig. 5, a front elevation of the tumbler-gear portion of the device; Fig. 6, a sectional plan of the same in the plane of line *b* of Figs. 3 and 4; Fig. 7, a front elevation of the sliding gear portion of the device; Fig. 8, a vertical longitudinal section of the same in the plane of line *c* of Figs. 3, 4, and 9; Fig. 9, a plan of the same; and Fig. 10 a front elevation of the fixed frame parts, with the tumbler and all gearing omitted.

In the drawings, referring for the present exclusively to Figs. 1 and 2, 1 indicates one of the terminal shafts of a pair, the same to be mounted in a suitable bearing and being herein termed the "driving-shaft;" 2, the other terminal shaft of the pair and herein termed the "driven shaft," the same being splined and disposed parallel with the driving-shaft and to be mounted in suitable bearings; 3, a pinion on the driving-shaft; 4, an idle gear engaging pinion 3; 5, an idle pinion fast with gear 4; 6, an idle pinion engaging gear 4; 7, an idle gear engaging pinion 5; 8, an angularly-adjustable tumbler; 9, its axis of oscillation; 10, a detent for holding it in angularly-adjusted position; 11, an idle pinion loose on the axis of the tumbler and engaging pinion 6; 12, an idle pinion loose on the axis of the tumbler and engaging gear 7; 13, an idle pinion carried by the tumbler and engaging pin-

ion 11; 14, an idle pinion carried by the tumbler and engaging pinion 12; 15, an idle pinion fast with pinion 14 and of lesser diameter; 16, a gear splined on driven shaft 2 and adapted to be shifted into the vertical plane of either pinion 13, 14, or 15, and 17 a pinion fast with gear 16 and adapted by the sliding of the gear and pinion on the driving-shaft to be brought into the vertical plane of either pinion 13 or 14.

In Fig. 1 it will be observed that driven shaft 2 is disposed above pinions 13, 14, and 15, so that by the upward adjustment of the tumbler any one of those pinions can be caused to engage with the driven gears, according to which of them has been longitudinally shifted to the plane of the selected tumbler-pinion to be engaged. In Fig. 2 the driven shaft, with its gear and pinion, has been diagrammatically displaced to the right in order to uncover the tumbler-gearing below it. Looking at Fig. 2, it will be observed that members 4, 6, 11, and 13 constitute an idle transmitting train of gears from pinion 3, having no effect in modifying speed received from pinion 3 and ultimately transmitted from pinion 13, and it will be manifest that the size of the members referred to is immaterial so far as speed conditions are concerned, their proper engagement for purposes of transmission being the controlling element as to the size of these members. Assume pinion 3 and gear 16 to have an equal number of teeth and that gear 16 is shifted longitudinally into the plane of and caused to engage with pinion 13. Under these conditions the gearing will effect no modification of speeds and the driven shaft will run at the speed of the driving-shaft. Assume again that pinion 17 had half as many teeth as pinion 3 and that pinion 17 is engaging with pinion 13. Under these conditions the driven shaft will turn at twice the speed of the driving-shaft, the entire modification of speed being effected by pinions 3 and 17, members 4, 6, 11, and 13 constituting an idle or unmodifying transmitting-train. Pinion 5 receives its motion from pinion 3 through gear 4, which gear, while an unmodifying idler under the conditions previously referred to, becomes a modifier in connection with the train deriving its motion from pinion 5. Pinion 5 and gear 4

together form a compound idler. The speed as modified by the compound idler becomes effective on tumbler-pinion 14, the consequence being that pinions 13 and 14 have different speeds. If now gear 16 be engaged with pinion 14, the driving-shaft will have a much lower speed than was the case when gear 16 engaged with pinion 13, and, correspondingly, if pinion 17 be engaged with pinion 14 the driving-shaft will have a much lower speed than was the case when pinion 17 engaged with pinion 13. In this transmission of motion from pinion 5 to the driven shaft the members 7, 12, and 14 constitute an unmodifying transmitting-train. While pinion 14 was an unmodifying idler under the conditions just named, it, in connection with pinion 15, forms a compound idler, serving to reduce the speed when pinion 15 becomes involved in the transmission. If gear 16 be engaged with pinion 15, then the driving-shaft will be given a much slower speed than under any of the previously-mentioned conditions. Five changes of speed for the driven shaft are thus provided for with but two wheels upon it, and the system is such as to permit of a very useful series of speeds—that is to say, the system lends itself to a graduated series of selective speeds. While the illustration shows but two wheels on the driven shaft and three idlers carried by the tumbler to drive those wheels, it is manifest that the system will lend itself to any desired extension. The initial compound idler, formed by gear 4 and pinion 5, derives constant speed from pinion 3, and it is manifest that this compound idler might very properly be viewed as the real driver of the system, pinion 3 being a mere expedient for giving motion at constant speed to this compound idler. While I have denominated shaft 1 as the "driving-shaft," under which circumstances pinion 3 might be called the "driving-pinion," I will refer to the initial idler formed by gear 4 and pinion 5 as the "compound driving-gear."

I will now proceed to describe the exemplifying system of supporting-framing and the device for adjusting the wheels that are splined on the driven shaft.

Proceeding with the drawings, 18 indicates a main frame-plate, which may be taken as typifying any suitable supporting-surface found or supplied about any machine in connection with which my speed-changing device is to be employed—as, for instance, the outer end face of the head-stock of an engine-lathe, driving-shaft 1 and the supporting-stud of compound driving-gear 4 finding their support in this frame-plate; 19, a double hanger secured against the frame-plate and carrying the bearings for driven shaft 2 at such distance apart as will permit the proper endwise shifting of united wheels 16 and 17 upon the driving-shaft to bring them into the proper planes of the tumbler-pinions; 20, a longitudinal guideway in the top of this

hanger parallel with the driven shaft; 21, a cross-head sliding in this guideway and having rack-teeth in its edge; 22, a fork projecting downwardly from this cross-head and straddling gear 16, so that the shifting of the cross-head effects the shifting of wheels 16 and 17 upon the driven shaft; 23, a cover-plate secured to the top of the hanger and roofing the guideway therein; 24, a hand-crank journaled in the cover-plate; 25, a gear fast on the shaft of this crank and gearing with the cross-head, whereby the turning of the crank shifts the cross-head and the wheels of the driven shaft; 26, a spring-detent carried by crank 24 and adapted to engage selective detent-holes in the cover-plate, and thus fix the wheels on the driven shaft in their various positions of longitudinal adjustment; 27, a tumbler bearing-plate secured against the main frame-plate and adapted for swiveling motion thereon, with the axis 9 of the tumbler as the axis of swiveling; 28, slots in plate 27 for the bolts uniting it to frame-plate 18, these slots permitting a limited swiveling motion of the plate about axis 9; 29, a bracket reaching outwardly from tumbler bearing-plate 27 and in conjunction with the bearing-plate supporting the axial stud 9 of the tumbler, which tumbler swings on that portion of the axial stud exposed within the opening of the bracket 29; 30, hubs projecting from each face of the tumbler 8 concentric with its axis 9 and fitting between the supporting-bearings of the stud 9, pinion 11 turning freely on one of these hubs and pinion 12 turning freely on the other one of them; 31, a cylindrical boss projecting from the rear face of the tumbler concentric with the common axis of pinions 13 and 14, pinion 13 turning freely on this boss; 32, a stud passing through this boss and having a collar on its inner end to retain pinion 13 in its place, its forward end projecting from the tumbler to furnish a journal on which loosely turns united pinions 14 and 15, this stud having on its outer end a nut and washer to retain these pinions and the stud in place, and 33 the supporting-stud of idle gear 7, the same being mounted in a slot in tumbler bearing-plate 27 and adjustable to a limited degree in an arc substantially concentric with tumbler-axis 9.

The manner of adjustment of wheels 16 and 17 on the driving-shaft to bring a selected one of them into the plane of the selected one of the tumbler-pinions will be obvious from the construction, as will also be the manner of angularly adjusting the tumbler to bring the selected wheels into engagement. The tumbler being mounted in a structure independent of the structure supporting the driven shaft and the one supporting the initial gearing permits of relative adjustment or change in location to suit various sizes of gearing. The mounting of the gearing directly engaging the tumbler-gears upon tumbler bearing-plate 27 permits of the tumbler and its ad-

5 juncts being constructed, assembled, and adjusted as a suborganization, and the adjustment of stud 33 in the tumbler bearing-plate permits of idle gear 7 being brought nicely into proper engagement with pinion 5, it being observed that the tumbler-axis calls for a certain accurate relationship with the axis of pinion 6 and gear 7.

10 Shaft 1 has been spoken of as the "driving-shaft" and shaft 2 as the "driven shaft;" but it is manifest that the offices of these two shafts may be transposed, and the same consideration applies if instead of shaft 1 being employed a shaft turning with the compound gear 4 5 be used.

15 I claim as my invention—

1. In a speed-changing device, the combination, substantially as set forth, of a compound driving-gear, an angularly-adjustable tumbler, an idle gear carried for adjustment by the tumbler, a compound idle gear carried for adjustment by the tumbler, independent trains of idle gears connecting said compound driving-gear with the gears carried by the 25 tumbler, a driven shaft, and a gear on the driven shaft and mounted for longitudinal adjustment into the selective plane of gears carried by the tumbler.

2. In a speed-changing device, the combination, substantially as set forth, of a compound driving-gear, an angularly-adjustable tumbler, an idle gear carried for adjustment by the tumbler, a compound idle gear carried for adjustment by the tumbler, independent 35 trains of idle gears connecting said compound driving-gear with the gears carried by the tumbler, a driven shaft, and a plurality of gears on the driven shaft and mounted for longitudinal adjustment into the selective 40 plane of gears carried by the tumbler.

3. In a speed-changing device, the combination, substantially as set forth, of an angularly-adjustable tumbler, hubs projecting from the tumbler concentric with its axis, 45 gears loose on said hubs, gears engaging said gears and mounted free of the tumbler, a compound gear engaging the last-mentioned gears, idle gears carried by the tumbler and engaging the first-mentioned gears, and a longitudinal-adjustable gear mounted free of the tumbler and adapted for engagement selectively with said idle gears.

4. In a speed-changing device, the combination, substantially as set forth, of an angularly-adjustable tumbler, hubs projecting from the tumbler concentric with its axis, 55 gears loose on said hubs, gears engaging said gears and mounted free of the tumbler, a compound gear engaging the last-mentioned gears,

60 gears, a boss projecting from the tumbler eccentric to said hubs, an idle gear loose on said boss and engaging one of the first-mentioned gears, a stud passing axially through said boss and projecting from the side of the 65 tumbler opposite the boss, an idle gear mounted on the projection of said stud and engaging the second one of the first-mentioned

gears, and a longitudinally-adjustable gear mounted free of the tumbler and adapted for engagement selectively with said idle gears. 70

5. In a speed-changing device, the combination, substantially as set forth, of a double bearing-bracket, a stud mounted in said bearings, a tumbler mounted for angular adjustment on said stud between said bearings, hubs 75 projecting from the tumbler to the bearings and surrounding the stud, central gears mounted to turn on said hubs, idle tumbler-gears carried by the tumbler and engaging said central gears, a longitudinally-adjustable 80 gear mounted free of the tumbler and adapted for engagement selectively with said idle gears, idle gears mounted free of the tumbler and engaging said central gears, and a compound gear engaging the last-mentioned 85 gears.

6. In a speed-changing device, the combination, substantially as set forth, of a tumbler-pivot, a tumbler bearing-plate mounted for angular adjustment on said pivot, a tumbler 90 mounted for angular adjustment on said pivot, gears mounted on the tumbler, and gears arranged for coöperation with said gears.

7. In a speed-changing device, the combination, substantially as set forth, of a tumbler-pivot, a tumbler bearing-plate mounted for angular adjustment on said pivot, a tumbler 95 mounted for angular adjustment on said pivot, a gear mounted concentric with said pivot, a gear carried by the tumbler and co-operating with said gear, a gear free of the tumbler and co-operating with said concentrically-mounted gear, and a gear carried by 100 said tumbler bearing-plate and engaging the first-mentioned gear. 105

8. In a speed-changing device, the combination, substantially as set forth, of a tumbler-pivot, a tumbler bearing-plate mounted for angular adjustment on said pivot, a tumbler 110 mounted for angular adjustment on said pivot, a pair of gears mounted concentric with said pivot, adjustable gears carried by the tumbler and co-operating with said gears, a gear free of the tumbler and co-operating with said concentrically-mounted gear, a gear 115 mounted on said tumbler bearing-plate and engaging one of the first-mentioned gears, and a second gear mounted for angular adjustment on the tumbler bearing-plate and engaging the other one of the first-mentioned 120 gears, and a compound gear engaging the two gears mounted on the tumbler bearing-plate.

9. In a speed-changing device, the combination, substantially as set forth, of a main frame-plate, a bracket mounted thereon, an 125 angularly-adjustable tumbler mounted in the bracket, a second bracket mounted on the frame-plate, a shaft journaled in the second bracket and forming one terminal of the transmission system, a gear on said shaft, gearing 130 forming the other terminal of the transmission system, and co-operating gearing on the tumbler and frame-plate to serve as intermediate members of the transmission system.

10. In a speed-changing device, the combination, substantially as set forth, of a main frame-plate, a bracket mounted adjustably thereon, an angularly - adjustable tumbler
5 mounted in the bracket, a second bracket mounted on the frame-plate, a shaft journaled in the second bracket, gears carried by the tumbler and shaft, and gearing mounted free of the tumbler and coöperating with the gears
10 thereon.
11. In a speed-changing device, the combination, substantially as set forth, of a driving-pinion, a compound driving-gear engaged by said pinion, an angularly-adjustable tumbler,

an idle gear carried for adjustment by the tumbler, a compound idle gear carried for adjustment by the tumbler, independent trains of idle gears connecting said compound driving-gear with the gears carried by the tumbler, a driven shaft, and a gear on the driven shaft and mounted for longitudinal adjustment into the selective plane of gears carried by the tumbler.

WILLIAM T. EMMES.
